UNITED STATES PATENT OFFICE

THOMAS JACKSON ZIMMERMAN, OF ARCADIA, FLORIDA

GUN HOLDING DEVICE

Application filed December 5, 1929. Serial No. 411,930.

This invention relates to improvements in gun retaining or holding devices and has for an object to provide a clamp especially adapted for use in holding or retaining guns in rest positions upon automobiles and like vehicles, for the express purpose of preventing injury to the vehicle occupants in event of accidental discharge thereof, the arrangement and construction of the device being such that a gun may be conveniently and quickly engaged in the same and when so engaged, positively prevented from accidental or undue displacement, yet, which, when it is desired, may be instantly released to allow the removal of the engaged gun.

Another and equally important object of the invention may be stated to reside in the provision of a device of the character mentioned comprehending a novel form of bracket-like securing means, which, when in closed position, will have yieldable and positive engagement with the barrel or other adjacent portion of a gun introduced thereto and also, may be locked in such closed position to avoid accidental disengagement, and, to a great extent, theft of said engaged gun.

Other objects of the invention will be in part obvious and in part pointed out hereinafter.

In order that the invention and its mode of operation may be readily understood by persons skilled in the art, I have in the accompanying illustrative drawings, and in the detailed following description based thereon, set out several possible embodiments of the same.

In these drawings:—

Figure 1 is a fragmentary side elevation of a motor driven vehicle having the improved gun holding device attached thereto and showing the arrangement of a gun in the same;

Figure 2 is an enlarged longitudinal section taken on the line 2—2 of Figure 1 looking in the direction in which the arrows point;

Figure 3 is a detail in side elevation of the improved device, and

Figure 4 is a longitudinal section through a slightly modified form of the device.

Having more particular reference to the drawings, in connection with which like characters of reference will designate corresponding parts throughout, the invention may be stated to comprise a cup-like body portion, constructed of metal or other suitable material, indicated by the numeral 1, the normally outer end of said body portion being open while attaching brackets or feet 2 are fixedly secured to the opposite end thereof and are adapted to be arranged in positions adjacent one side of the exterior portion of an automobile cowl C, by passing suitable fastening devices to apertures formed in the extremities of said feet into engagement with adjacent portions of the cowl, as indicated by the numeral 3.

Slidably received within the open and normally outer end of the body portion 1 is a shank or piece 4, the inner end of which is adapted to have bearing engagement upon the adjacent end of an expansible coiled spring 5 arranged within said body portion 1 and having its opposite end bearing upon an adjacent portion of the closed end of said body portion, as is clearly shown in the Figure 2. In order that limited sliding inward or outward movement of the piece 4 will be permitted and also, that the expansible coiled spring 5 may, under all conditions, be retained under a certain degree of tension by the slidably introduced piece 4, I engage through one side wall of the body portion 1, a stop or set screw 6, the inner end of which is adapted to be engaged in a slot 7 formed in an adjacent portion of the piece 4 and disposed longitudinally thereof. Upon the outer end of the piece 4, I provide a cradle-like device or saddle 7' which, if desired, may have its outer face covered with a suitable hiding material, such as leather, fabric or the like (not shown herein).

Fixedly mounted upon or formed integral with one side of the body portion 1 adjacent the open and normally outer end thereof is a curved bearing lug 8 to which, there is pivotally connected, as at 9, a segmental or curved link 10, the opposite or free end of which has a second and substantially straight link 11 pivoted to the same as indicated by the nu-

meral 12, the free portion of this straight link 11 being forked or bifurcated as indicated by the numeral 13 and pivotally receiving between the extremities of the bifurcated portions, through the medium of a pivot pin, rivet or the like, as at 14, a hasp-like arm 15. In this connection, it will be noted that the hasp-like arm 15 is provided with an intermediate arranged opening 16 adapted to be engaged over or to receive a staple or similar device 17 therethrough, the latter being fixedly carried upon an adjacent or corresponding portion of the body portion 1, while the free portion of said arm 15 is curved upon itself as indicated by the numeral 18, whereby to facilitate engagement therewith, especially, at a time when the hasp is engaged over its staple 17. Furthermore, it is to be noted that the normally inner end of the hasp-like arm 15, that is, the end of the same adjacent its point of pivoting, as at 14, to the bifurcated portion 13, is formed with a curved or cam-like bearing surface 19, the purpose of which will be presently described.

25 which will be presently described.
Fixedly secured to or formed integral with
a portion of the body portion 1, in opposed
relation to the lug 8, is a second lug or keeper
lug 20, one side of which is formed with a
curved or cam-like bearing surface 21, corre-
sponding in curvature to that of the bearing
surface 19 formed upon the normally inner
end of the hasp-like arm 15.

35 Fixedly carried upon the normally inner side of the intermediate portion of the curved or segmental link 10, is an arm 22 formed upon its free end with a saddle-like piece 23, corresponding to the saddle 7' carried upon the opposed end of the slideable piece or shank 4. In this connection, it will be 40 noted that with closing of the device, that is, movement of the same to the position as is shown in the Figure 2, the arm 22 with its saddle 23 will be arranged in longitudinally opposed relation with respect to the saddle 45 7' upon the shank or piece 4.

7 upon the shank or piece 4.
In usage of the improved gun retaining device, it will be noted, upon reference to the Figure 1, that the same is secured to one side of an automobile cowl C, preferably, in 50 proximity to the curved top thereof and that the article or gun embracing means constituted by the lug 8, the segmental link 10 and the straight link 11 together with the hasp 15 are arranged for movement in a horizontal 55 plane. Also, as a means to receive the butt of the stock of a gun G whereby to retain the same upon the adjacent running board of an equipped automobile, I provide a cup-like retaining device 24, the shape and size of 60 which is such as to permit of ready yet comparatively snug placement and reception of the gun stock butt therein, in the fashion as is shown in the Figure 1; particular attention being invited to the fact that this cup-like stock butt receiving cup is so positioned 65

upon the automobile running board b , as to permit the positioning of the gun, at rest position, in a substantially vertical plane. The cup 24, of course, may be fixedly secured to the proper portion of the running board b , 70 by passing suitable fastening devices through the bottom thereof and into engagement with adjacent portions of said running board and furthermore, it will be understood and appreciated, that the bottom of this cup may be provided with a suitable cushion (not shown herein), as for example, a sheet of rubber, felt or other material, for the purpose of providing a cushioning support for the gun and also, for preventing mutilation of the 75 stock butt. 80

To engage the gun G in the holding device, the article embracing means comprehending the segmental link 10, the straight link 11 and the hasp 15, are swung to that open position as is shown in dotted lines in the Figure 2. At this time, the gun stock 85 butt is inserted within the receiving cup 24 whereupon the upper portion of the gun and in most instances, the barrel thereof, is engaged upon the saddle portion 7' of the slide- 90 able shank or piece 4. At this time, the article embracing means comprehending the segmental link 10, the straight link 11 and the hasp 15, are swung to their closed positions, as is shown in full lines in the Figure 95 2; the hasp being engaged over the staple 17 whereupon a padlock, pin or other suitable fastening device (not shown herein) may be passed through the staple to prevent undue 100 or accidental disengagement of said hasp 15 from said staple. At this time, it will be noted that the saddle 23 upon the arm 22 carried by the segmental link 10 will have been brought into binding engagement with the adjacent portion of the gun G and in doing so, will impart an inward thrust thereto. This inward thrust of the engaged portion of the gun G, of course, will impart similar movement to the shank or piece 4 which is 105 slidably mounted in the body portion 1 and by consequence, the expansible coiled spring 5 within said body portion will be placed under a tension and this tension will be such as will cause the engaged portion of the gun to be yieldably gripped between the saddle pieces 7' and 23, hence, to prevent accidental or undue displacement of the engaged gun. Also, particular attention is invited to the fact that when the hasp 15 is 110 moved to its closed position with respect to the staple 17, the bifurcated portion 13 of the straight link 11 will have straddling-like engagement over the fixedly mounted lug 20, aforesaid, and at this time, the curved hasp-like arm 15 with its cam bearing surface 115 21 will be brought into bearing contact with the correspondingly curved portion 21 of said lug 20. Hence, as the hasp-like arm 15 is swung inwardly upon its pivot pin 14, the 120 130

engaged cam-like bearing surfaces 19 and 21 will cause the hasp-like arm 15 to impart a slightly inward pull to the straight link 11 and consequently, to the segmental link 10, thereby ensuring a binding or gripping engagement of the saddle 23 carried upon the arm 22 upon the adjacent or engaged portion of the gun G. Furthermore, this peculiar construction of the inner end of the hasp 15 and the inner side of the lug 20 is such that when the hasp 15 with its curved bearing surface 19 is engaged with the curved bearing surface 21 of the lug 20, accidental or undue lateral movement of said inner end of the hasp 15 with respect to the lug 20 will be prevented and because of this, a positive locking or securing connection as between said lug 20 and the hasp 15 will be ensured.

To remove the gun G from the holding device, it is only necessary that the padlock or pin be removed from the staple 17, whereupon the hasp 15 is swung outwardly together with the links 10 and 11, to their open positions, allowing the gun G to be readily removed therefrom as well as from the cup 24.

In the Figure 4, I have shown a modified form of the holding or securing device, in which there is provided, a body portion 1' equipped with fixedly mounted attaching brackets feet 2' adapted to be secured to an appropriate or desired portion of an automobile body equipped with the invention. Apertured ears or lugs 25 are fixedly mounted upon or formed integral with the opposite sides of the normally outer end portion of the body 1' and serve to pivotally receive and support, as at 26, bracket arms 27, the outer extremities of which are formed with relatively inwardly curved extensions 28. A looped spring 29 is adapted to be arranged intermediately of the normally inner portions of the brackets 27, the loop portion of said spring resting upon a seat 30 provided therefor in the adjacent part of the body portion end, as is clearly shown in said Figure 4. The end portions of this looped spring are crossed, as is shown in the drawings and the free ends of the spring are attached to intermediate portions of the brackets 27 as indicated by the numeral 31, such attachment being effected in any suitable manner, as for example, passing the free ends of the looped spring through openings formed in adjacent portions of the bracket and then upsetting the extremities of the same to prevent disengagement. By reason of the positioning of the looped spring 29 between the inner portions of the brackets 27 and the connection of the free ends of said spring to the intermediate portions of these brackets, it will be understood that the inwardly curved normally inner ends of the same will be normally urged in directions toward each other. Consequently upon this, with the interposition-

ing of a gun barrel G' or other portion of a gun between the fingers, as is clearly shown in the figure, said brackets will have a yieldable or gripping engagement with the same and because of the formation of the curved extremities 28 thereupon, will afford effectual means for preventing accidental or undue lateral displacement of the gun with relation to the device.

If desired, portions of the inner sides of the brackets 27 may be formed with curved seats, as indicated by the numeral 32, these seats being in relatively opposed relation and being adapted to receive adjacent portions of the gun introduced between the brackets, 80

In using the form of invention disclosed in the Figure 4, it is to be understood that a stock butt retaining cup such as indicated in the previous embodiment of the invention 85 by the numeral 24, is employed in the same manner as it is used in said previous embodiment. Consequently, with positioning of the stock butt in the retaining cup 24, the upper portion of the gun may be then moved inwardly through the curved extremities 28 of the brackets 27, thus forcing the same apart against the tension of the looped spring 29 until the gun barrel or other engaged portion is moved to that position as is shown in the Figure 4, whereupon, due to the spring urge imparted to the brackets 27 from the spring 29, the same would effect a gripping or embracing engagement of the inserted gun and thus, will serve to effectually retain the same 95 in its position of rest or retention with respect to the automobile carrying the invention. 100

Manifestly, the construction shown is capable of considerable modification, and such modification as is within the spirit of my claims I consider within the spirit of my invention.

I claim:—

1. A device of the character described, comprising a body portion, an arm slidably received by said body portion, spring means arranged in the body portion having bearing upon said arm for normally imparting an outward thrust to the same, and article embracing means swingably connected at one end to said body portion and cooperable with said arm, the remaining end of said article embracing means being adapted to have detachable connection with the body portion.

2. A device of the character described, comprising a body portion, an arm adjustably retained by said body portion adapted to be normally thrust outwardly with respect thereto, pivotally interconnected links, one of said links being pivotally connected to the body portion, a hasp pivotally connected to the free end of an opposite link, keeper means on the body portion having a cam-like bearing surface, and that end of said hasp

adjacent its pivotal mounting being formed with a cam bearing means cooperable with said first cam bearing means.

3. A device of the character described comprising a body portion, an arm slidably received by said body portion, spring means in the body portion engaging said arm for normally imparting an outward thrust thereto, a plurality of pivotally interconnected links, one of said links being pivotally connected to said body portion, an arm pivotally connected to the free end of the remaining link, a keeper means upon the body portion having one of its sides formed with a cam-like bearing surface, said arm having that end of the same adjacent its pivotal connection to said link formed with a cam bearing surface cooperable with the cam bearing surface of the keeper means, and means on the body portion engageable with said arm for effecting detachable securing of the same to the body portion.

4. In combination with a supporting device, a cupped gun stock butt retaining means, and a gun barrel engaging device secured to said supporting means in spaced relation to said gun stock but receiving means and comprising a body portion, an arm adjustably retained by said body portion and adapted to have a normally outward thrust imparted thereto, and article embracing means swingably connected at one end, to said body portion cooperable with said arm, at times, and the remaining end of said article embracing means having detachable engagement with the body portion.

In witness whereof I have hereunto set my hand.

THOMAS JACKSON ZIMMERMAN.
